UNITED STATES PATENT OFFICE.

CHARLES A. BREWER, OF NOROTON HEIGHTS, CONNECTICUT, ASSIGNOR TO CANNON ENGINEERING CO., OF BROOKLYN, NEW YORK, A CORPORATION OF NEW YORK.

INDICATOR FOR STEAM PRESSING IRONS.

Application filed January 29, 1926. Serial No. 84,612.

This invention relates, generally, to improvements in steam pressing irons; and the invention has reference, more particularly, to a means for visibly indicating to the user 5 the working conditions of the pressing face of the iron.

In the use of steam pressing irons, in which conditions of both heat and moisture are involved, it is highly desirable that the operator be aware that the right conditions with respect to heat and moisture are maintained; since, if the temperature of the iron is allowed to rise too high, not only does the extravasated steam approach the so-called dry 15 condition in which its dampening effect upon the goods being pressed is impaired or diminished, but the body of the iron may become hot enough to damage said goods by scorching or burning; while, on the other hand, if 20 the temperature of the iron is allowed to drop too low, not only is the pressing efficiency of the iron impaired, but the steam within the same tends to condense, whereby water is extravasated from the pressing face of the 25 iron upon the goods, with the consequent likelihood of soiling or staining the latter.

It is the object of this invention to provide a novel means for visibly indicating the working condition of a steam pressing iron, 30 with particular reference to conditions at the pressing face thereof; and, to this end, the invention consists in a novel construction and arrangement of thermometric indicating means, having a novel association with the iron bottom, together with a novel arrangement of indicator plate with which said 35 thermometric means cooperates.

The invention is clearly illustrated in the accompanying drawings, in which:—

40 Figure 1 is a side elevation of a steam pressing iron equipped with the novel visible indicating means made according to and embodying the principles of this invention; Figure 2 is in part a side elevation and in part 45 a longitudinal section of said steam pressing iron, the indicator plate being removed; Figure 3 is a transverse section, taken on line 3—3 in Figure 1; and Figure 4 is a fragmentary transverse section, taken on line 50 4—4 in said Figure 2.

Similar characters of reference are employed in all of the hereinabove described views, to indicate corresponding parts.

Referring now to said drawings, the reference character 5 indicates the body portion

of the iron, which is suitably constructed to provide an internal steam chamber 6 above its pressing face portion 7. Suitably connected with the body portion 5 is a top-casing or cover member 8, to the upper side of which 60 is fastened the handle-member 9 by which the iron may be manipulated. Connected with the heel of said body portion 5 is a steam-intake means 10 for delivering steam from a suitable source into said steam chamber 6. 65 The free end of said steam-intake means 10 is provided with a coupling-neck 11 for the attachment therewith of a flexible steam delivery conduit or hose (not shown) which leads from the steam supply or source. The 70 pressing face portion 7 is provided with a plurality of suitably disposed perforations or openings 12 which lead from said steam chamber 6 to the bottom or pressing face 13 of the iron body, and through which steam is 75 extravasated to the goods being pressed by the iron.

Connected with the upper side of said body 5, within the casing 8 is an electrical heating unit 14 of any suitable type. Connected with the rear end of said casing 8, so as to project exteriorly therethrough, are insulated contact-pins 15 to receive a suitable coupling means for electrically connecting the iron in a service circuit in the usual 80 manner. Mounted within said casing 8 is a thermostatic circuit breaker or switch 16, provided with suitable means 17 for adjusting the same. Said heating unit 14 and thermostatic switch 16 are electrically connected in series between the respective contact-pins 15.

The novel visible indicating means, provided in connection with the iron body 5, is arranged and constructed as follows:

Said iron body 5 is provided, in connection with one side thereof, with a longitudinal external cavity or housing chamber 18. Extending inwardly from said external cavity or housing chamber 18 is a lateral branch or pocket 19, the inner end of which is disposed in the pressing face portion 7 of said iron body 5, and preferably in a substantially central location relative to the same. Arranged within said cavity or housing chamber 18 and its branch or pocket 19 is a thermometric indicator comprising a transparent tubular element 20 provided with a lateral extension 21 terminating in a bulb portion 22 adapted to contain a tem- 100 105 110

perature responsive fluid 23. Said thermometric indicator, when assembled with the iron body 5, has its inner lateral extension 21 entered within said branch or pocket 19, with the bulb-portion 22 situated in the inner end of said branch or pocket 19, and thus imbedded within the pressing face portion 7 of said iron body; the outer portion or element 20 of said thermometric indicator 10 extends longitudinally within said external cavity or housing chamber 18. The thermometric indicator is retained in the described assembled relation by a suitable fastening means, preferably in the form of a 15 metallic clip 24, the base 25 of which is secured to the rear wall of said cavity or housing chamber 18 by a fastening screw 26, while the main portion thereof passes externally around the element 20 so as to firmly 20 embrace and retain the same against movement, and at the same time to hold the lateral extension 21 and its bulb portion 22 against outward withdrawal from the branch or pocket 19. The outer open side of said 25 external cavity or housing chamber 18 is closed by a transparent panel 27, preferably made of plate glass, and through which the tubular element 20 is visible. Said transparent panel 27 is inscribed with zone marks 30 dividing the same into a plurality of indicating zones, which are respectively designated with suitable inscriptions denoting conditions at the pressing face of the iron, to wit, "Water", "Steam press", "Scorch" 35 and "Burn." Said zones are so disposed in relation to the thermometric indicator as to cooperate with the movement of the temperature responsive fluid 23 thereof, in the manner clearly to be understood by an inspection of Figure 1 of the drawings.

In operation, electric current is served to the heating unit 14, and the body 5 of the iron is thereby heated to condition the same for service. As the temperature of the 45 pressing face portion 7 rises, the temperature responsive fluid 23 within the bulb portion 22 of the thermometric indicator will expand and thus be caused to travel outwardly through the lateral extension 21 50 and tubular element 20. When said fluid 23 in its movement enters or is visible through the zone of the transparent indicator panel 27 which is denoted "Steam press", steam from a suitable source is introduced 55 into the steam chamber 6, and the iron is thereupon ready for steam pressing operations.

As the operator manipulates the iron to press goods, the steam from the steam chamber 6 will be extravasated through the openings or perforations 12 of the pressing face portion 7 so as to be discharged with good dampening effect from the pressing face of the iron.

As use of the iron continues, if the temper-

ature at the pressing face portion 7 rises too high, the fluid 23 of the thermometric indicator will further expand, so that the same will progress or move on through the tubular element 20, and will enter or be visible 70 through the zones of the transparent indicator panel 27 denoted "Scorch" and "Burn", thus giving the operator a visible indication that the condition of the pressing face portion 7 of the iron is approaching an abnormal 75 overheated condition likely to result in injury to the goods as well as to reduce the efficiency of the steam pressing function thereof. Upon such indication the operator, may interrupt, regulate or reduce the electrical current 80 served to the heating unit to lower the temperature of the iron, and bring the same back to normal steam pressing condition; if, on the other hand, the temperature at the pressing face portion 7 drops too low, the fluid 85 23 of the thermometric indicator will contract, so that the same will retreat through the tubular element 20, and will be visible only through the zone of the transparent indicator panel 27 denoted "Water", thus giving 90 the operator a visible indication that the condition of the pressing face portion 7 of the iron is approaching abnormal underheated condition, likely to result in condensation of steam and consequent undesirable extravasation of water upon the goods, as well as 95 impairment of the pressing efficiency of the iron. Upon such indication the operator may make such adjustments of current service as may be required to raise the temperature, 100 and bring the same back to normal steam pressing condition.

One of the advantages of my novel arrangement and construction of thermometric indicator device is that the same is associated directly with the pressing face portion of the iron, which is the effective part of the iron with which the goods are engaged, and the working condition of which it is highly essential should be known to the operator. By reason of the direct and close cooperative association of the thermometric indicator with the pressing face portion of the iron, it follows that the indicator is quickly responsive and highly sensitive to every change in the 110 normal working condition of the pressing face portion, and that consequently the operator is given timely indication of abnormal conditions so that steps to correct the same may be taken before either damage to the 115 goods or undue lowering of the steam pressing efficiency of the iron results.

Having thus described my invention, I claim:—

1. In a steam pressing iron provided with 125 a body having a perforated pressing face portion and containing a steam chamber contiguous to said perforated pressing face portion, said body having an open housing chamber in a side thereof provided with a lateral 130

branch extending into said pressing face portion of said body, a thermometric indicator having its bulb end entered in said lateral branch and the free end portion of its tubular element disposed in said housing chamber, and a transparent indicator panel secured across said open housing chamber to overlie the exposed tubular element of said thermometric indicator, said panel being divided into zones denoting various working conditions at the pressing face portion of the iron.

2. In a steam pressing iron provided with a body having a perforated pressing face portion and containing a steam chamber contiguous to said perforate pressing face portion, a thermometric indicator having its bulb

end imbedded in said pressing face portion of said body and its tubular element projected exteriorly from said iron body, said iron body having an exteriorly open chamber to house 20 said exterior tubular element of said thermometric indicator, and a transparent indicator panel secured across said open chamber to overlie said exterior tubular element of said thermometric indicator, said panel being divided into zones denoting various working conditions at the pressing face portion of the iron.

In testimony that I claim the invention set forth above I have hereunto set my hand this 30 25th day of January, 1926.

CHARLES A. BREWER.
